UNITED STATES PATENT OFFICE.

MATHIAS MAGNUSON, OF CHICAGO, ILLINOIS.

NECKTIE HOLDER.

Application filed September 27, 1920. Serial No. 413,198.

To all whom it may concern:

Be it known that I, MATHIAS MAGNUSON, a citizen of the United States, residing at Chicago, in the county of Cook and State 5 of Illinois, have invented certain new and useful Improvements in Necktie Holders, of which the following is a specification.

This invention relates to neck tie holders, and has for one of its objects the provision 10 of simple and efficient means for holding neck ties and the like, for displaying them for sale or for keeping them in straight condition and easily accessible by the user.

Other objects will appear hereinafter.

15 Embodiments of my invention are illustrated in the accompanying drawings forming a part of the specification, and in which—

Fig. 1 is an elevation of a tie holder embodying my invention;

20 Fig. 2 is a section taken on line 2—2 of Fig. 1;

Figs. 3 and 4 are enlarged sections taken on lines 3—3 and 4—4 respectively, of Fig. 2;

25 Fig. 5 is a fragmental elevation of a tie holder embodying my invention of different form than that shown in Fig. 1;

Fig. 6 is a section taken on line 6—6 of Fig. 5;

30 Figs. 7 and 8 are enlarged sections taken on lines 7—7 and 8—8 respectively, of Fig. 5;

Fig. 9 is an enlarged fragmental view looking upwardly in the direction of arrow 35 9 in Fig. 5;

Fig. 10 is an elevation of a tie holder of still different form from that shown in Figs. 1 and 5 but embodying my invention;

Fig. 11 is a section taken on line 11—11 of Fig. 10;

Fig. 12 is an enlarged fragmental view looking at the back of one corner of the construction shown in Fig. 10; and

Fig. 13 is a section taken on line 13—13 of Fig. 11.

Referring particularly to Fig. 1 I have indicated a frame made up of horizontally disposed portions 15, 16 and 17 joined together by a vertical bar 18. On this frame 50 I have indicated three separate tie-holding elements, each substantially the same in form and construction. The frame shown in Fig. 1 is indicated as curved, but it will be apparent that this frame may be formed 55 cylindrical, such as indicated in Figs. 1 and

2 in my United States Patent No. 1,268,744, issued June 4, 1918.

In this construction I have provided a rod or stem 19 having a tie hook 20 at its upper end and a pair of diverging prongs 21 at its lower end, the prongs 21 being on an offset portion 22. The lower end of stem 19 is journaled in a bearing formed by a plate 23 secured over a recess in bar 16, as clearly indicated in Figs. 1 and 2. The upper end of stem 19 is journaled in a bearing formed by a plate 24 secured to member 15, as indicated in Figs. 1 and 2. The plate 24 has parts 25 bent backwardly with slots 26 there- 60 in adapted to engage the stem 19. On the stem 19 is an enlargement 27 adapted to press against the upper part 25 of plate 24. Under plate 24 is a spring 28 which presses against enlargement 27 and the lower part 65 25 of plate 24 thereby pressing the enlargement 27 against the upper part 25. This tends to hold the hook 20 at its upper terminal of movement.

In horizontal bar 17 is provided a tubular 80 bearing 29 held securely to the bar 17 by a strap 30 and screws passing through said strap into bar 17. Rotatably mounted in bearing 29 is a tube 31. At the lower end of tube 31 is fixed a plug 32, so that the plug 85 32 rotates with the tube 31. The upper end of the tube 31 is slotted as at 33, see Fig. 4, at one side and provided with an opening 34 at the other side. A pair of tie clamping jaws 35 are disposed in the slot 33. Each 90 jaw 35 has a rearwardly extending arm 36 and each arm has an opening 37 therein engaging the lower end of a prong 21 of stem 19. The openings 37 are sufficiently large to permit the movement of prongs 21 in opening and closing the jaws 35. The parts of the jaws 35 disposed within tube 31 are curved as at 38, see Fig. 4. These curves hold the jaws against longitudinal movements in the tube 31. On the top end of each 95 tube 31 is a washer 39 held in place by a screw 40 passing down into member 32.

The stem 19 and parts journaled in bearing 29 are free to oscillate on the axis of the stem 19. In Fig. 1 one of the stems 19 is 105 shown as being turned around sidewise, while the other two stems 19 are disposed so that their hooks and jaws stand outwardly. I provide a simple locking means for holding the jaws in their outward position comprising a recess 41 in member 17 with a 110

spring 42 in said recess and pressing against a ball 43 which engages a recess 44 in tube 31. Any other suitable locking means may be provided when desired.

5 In Figs. 5 to 9 inclusive, a different form of my invention is shown. In this form the stem, hook, jaws and arms are indicated as being formed of a single piece of bent wire with the middle of the wire forming hook 45 and next adjacent portions forming a stem 46 with the end portions 47 forming the clamping jaws having arms 48 thereon.

10 In this form the frame has a plurality of horizontal bars 49 joined by one or more vertical bars 50. In each of the intermediate bars 49 a bearing is formed sufficiently large to permit rotation of the two wires of stem 46. In the lower bar 49 a larger bearing is provided by forming a recess in said bar and 15 providing a strap 51 secured to said bar by screws or their equivalent. Disposed within this larger bearing is a tubular member 52 which has a plate 53 on the upper side of said lowest bar 49 secured in any suitable 20 manner such as by tongues 54 extending through and bent over each plate 53. At the lower end of the tubular member 52 is an angular plate 55 secured in any desirable manner such as by tongues 54 formed on 25 member 52 and extending through and bent over to hold said plate in position. The arrangement is such that the plate 55 rotates with the tubular member 52.

30 Pivoted on the plate 55, as at 56, are two angular levers 57. The upper ends of the angular levers are provided with openings through which arms 48 pass. The plate 55 is provided with arcuate slots 59 through which the ends of the arms 48 pass to engage levers 57. The lower ends of the levers 57 are connected together by a tension 35 spring 60.

35 In this form of my invention the tie-holding device is rotatable in the frame and may be held with the jaws extending outwardly 40 from the frame in the manner set forth in reference to the construction of Fig. 1, in which there is a spring 41 disposed within a recess 42 and pressing a ball 43 in a recess 44 in tubular member 52, see Fig. 8.

45 In Figs. 10 to 13 inclusive, is indicated another form of my invention. In this form a flat rectangular frame is indicated. Six tie holding elements are shown, but it will 50 be understood that this number may be varied as desired, since each element is similar in construction and operation with the others.

55 In this form the stem 46, tie hook 45, jaws 60 47 and arms 48 are indicated as being formed of a single piece of bent wire, but it will be understood that in either this form or the form shown in Fig. 5 these parts may be made in any desired manner. In this form 65 the tie holding member does not oscillate

as in the other forms referred to. The stem 46 is slidably mounted in horizontal bars 62. At the lower end of the stem in the form shown in Fig. 10 and Fig. 5, I preferably provide a tie member 63 which may be 70 formed of a piece of sheet material bent around the two adjacent parts of stem 46 with a tongue 64 extending between the jaws 47 and the stem 46 with a head 65 on the outer sides of the jaws 47, as clearly indicated in Fig. 12. This serves to hold the parts in better operative positions, but can be dispensed with without departing from my invention.

75 In the form of my device shown in Fig. 10 I also provide angular levers 57 pivoted as at 56 to the frame with the upper ends of these levers having perforations which engage the arms 48 of the tie clamp. The lower ends of the angular levers 57 are connected by a spring 60 to hold the jaws normally together and the tie hook in its uppermost position.

80 In the forms shown in Figs. 5 to 13 inclusive, by placing a tie on the hook 45 and pulling it downwardly on said hook, the arms 48 are pressed inwardly by levers 57, thereby forcing the jaws 47 apart so that the tie can be placed between them. Then, upon releasing the tie, spring 60 closes the 85 jaws and moves hook 45 to its uppermost position.

85 In the construction shown in Figs. 1 to 4 inclusive, a tie is placed upon the hook 20 and the latter pressed downwardly against 90 the influence of spring 28 which moves the prongs 21 in openings 37 of arms 36 to open jaws 35. The tie can then be placed between the jaws 35 and the pressure relieved from hook 20, when the spring 28 will move stem 100 19 upwardly, thereby moving prongs 21 in openings 37 to close jaws 35 again and move hook 20 to its uppermost position. The reversed movements will enable one to withdraw a tie from the device.

105 On the backs of members 62—62 in Figs. 10 and 11 I have indicated guides 66 in which is slidably mounted a mirror. The latter is adapted to be slid in behind the frame out of sight and brought out when 110 it is to be used.

I claim:

1. A neck tie holder comprising a tie hook; a pair of clamping jaws connected with the tie hook; an arm on each jaw; a pivoted link having an opening therein engaging the free end of each arm; and a spring connecting the links together and tending to hold said jaws together.

120 2. A neck tie holder comprising a single piece of wire forming a tie hook, a pair of tie clamping jaws, a stem connecting the hook and jaws, and an arm on each jaw; swinging links each having an opening therein engaging one of the arms and a 125 130

spring connected with said links tending to hold the jaws together.

3. A neck tie holder comprising a single piece of bent wire forming a tie hook, a 5 pair of clamping jaws, a connecting stem, and an arm on each jaw; and resilient means connected with said arms tending to hold the jaws together.

4. A neck tie holder comprising a single 10 piece of bent wire forming a tie hook, a pair of tie clamping jaws, a stem connecting said hook and jaws, and an arm on each jaw; swinging links each attached to one of said arms; and a spring connected with said links 15 tending to hold the jaws together and said hook in its highest position.

5. A neck tie holder comprising a stem; a tie hook at one end of said stem; a pair of tie clamping jaws at the other end of said 20 stem; two angular levers pivoted adjacent said clamping jaws and having perforations in corresponding ends; an arm on each jaw extending through one of said perforations; and a spring connected with said angular 25 levers adapted to hold said jaws together.

6. A neck tie holder comprising a frame having bearings therein; a tubular member journaled in one of said bearings; a stem journaled in said bearings and tubular mem-

ber; a hook and tie clamping jaws attached 30 to said stem; a plate attached to said tubular member; levers pivoted to the plate; arms on the jaws engaging said levers and a tension spring connecting said levers together.

7. A neck tie holder comprising a frame 35 having bearings therein; a tubular member journaled in one of said bearings; a stem journaled in said bearings and tubular member; a hook and tie clamping jaws attached to said stem; a plate attached to said tubular member; levers pivoted to the plate; 40 arms on the jaws engaging said levers and a spring connected with said levers.

8. A necktie holder comprising a frame; a stem rotatably mounted in the frame; a 45 hook attached to the top of said stem; a pair of clamping jaws attached to the lower end of said stem; an arm on each of said jaws; two angular levers connected with said stem and mounted for rotating about the axis of said stem, there being connections between said levers and said arms; and a spring connecting said levers together tending to hold the jaws against each other.

In testimony whereof I have signed my 55 name to this specification on this 11th day of September, A. D. 1920.

MATHIAS MAGNUSON.
